Primary Examiner—Jeffrey Asch*(74) Attorney, Agent, or Firm*—Banner & Witcoff, Ltd.(57) **CLAIM**

The ornamental design for a handset, as shown and described.

DESCRIPTION

FIG. 1 is a bottom view of a handset showing our new design with a keypad in a first in use position;

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a perspective front view thereof;

FIG. 8 is a perspective rear view thereof;

FIG. 9 is a front view showing the keypad in a second in use position thereof;

FIG. 10 is a left side view showing the keypad in the second in use position thereof;

FIG. 11 is a perspective front view showing the keypad in the second in use position thereof;

FIG. 12 is a rear view of the handset shown in FIGS. 1-7 with a pen removed from the handset for clarity thereof; and, FIG. 13 is a perspective rear view of the handset shown in FIGS. 1-7 with a pen removed from the handset for clarity thereof.
